CLAIM

The ornamental design for a floor tile connector, as shown and described.

DESCRIPTION

FIG. 1 is a left side, bottom, perspective view of a floor tile connector;

FIG. 2 is a bottom plan view of the floor tile connector of FIG. 1;

FIG. 3 is a top plan view of the floor tile connector of FIG. 1; and,

FIG. 4 is a right side view of the floor tile connector of FIG. 1.

The design is the portion of the floor tile connector shown in solid lines in the drawing.
